UNITED STATES PATENT OFFICE.

DUDLEY NEWTON, OF SAN FRANCISCO, CALIFORNIA, ASSIGNOR OF ONE-HALF TO
WILLIAM A. GOERICKE.

DEVICE FOR FLUSHING TOILET FIXTURES.

Application filed June 14, 1921. Serial No. 477,437.

To all whom it may concern:

Be it known that I, DUDLEY NEWTON, a citizen of the United States, residing at San Francisco, in the county of San Francisco, and State of California, have invented new and useful Improvements in Devices for Flushing Toilet Fixtures, of which the following is a specification.

The present invention relates to apparatus for automatically flushing toilet fixtures such as water closets, urinals and the like and has special regard to certain improvements in apparatus of the character embodied in United States Letters Patent, Numbers 1,201,752 and 1,328,445, issued to me on Oct. 17, 1916, and Jan. 20, 1920, respectively.

The primary object of the invention is to provide apparatus of the character described which will be more simple as to construction, less expensive, more compact, easier to install and take down and also easier to clean, than similar apparatus heretofore used; these objects being attained principally thru the use of a novel and simplified form of siphon apparatus and by reason of the manner of housing and positioning or the locating of the same.

The invention possesses other advantages and features some of which, with the foregoing will be set forth at length in the following description where I shall outline in full that form of the invention which I have selected for illustration in the drawings accompanying and forming a part of the present specification. In said drawings I have shown one form of the construction of my invention, but it is to be understood that I do not limit myself to such form since the invention as expressed in the claims may be embodied in a plurality of forms.

Referring to the drawings:

Figure 1 is a fragmentary vertical sectional view of the apparatus of this invention shown applied to a urinal.

Figure 2 is an enlarged vertical fragmentary section thru the flushing tank taken at right angles to Fig. 1.

Figure 3 is an enlarged fragmentary vertical sectional view taken thru the fixture bowl and showing the siphon construction.

Figure 4 is a fragmentary top plan view of the construction shown in Fig. 3.

Figure 5 is an enlarged vertical sectional view of a modified form of fixture and siphon constructed of metal.

Figure 6 is top plan view of the apparatus shown in Fig. 5.

The present embodiment of the invention as shown in the drawings comprises a urinal 1 of porcelain, supported on the usual back or wall slab 2 behind which is a flushing tank 3 supported in any suitable manner above the urinal. The tank 3 contains the usual filling and level control apparatus, not shown.

A siphon 4 is mounted in the tank 3 and comprises a cover 5 or air container thru the top of which an air inlet pipe 6 extends in an inverted U form. The intake end of the pipe is near but spaced from the bottom of the tank. The other leg of the pipe 6 extends down into the longer leg 7 or discharge pipe of the siphon, which leg leads to and is formed integral with a trap 8. A short pipe 9 communicates with the outlet end of the trap, extends thru the back 2 and is connected with a flushing pipe 10 which latter extends into the top of the urinal.

A pipe 11 leads from the inlet side of the trap 8 downwardly, then thru the back 2 at a point below the urinal and then upwardly as at 12 whereby a trap as shown at 13 is provided in the pipe 11.

The lower side of the porcelain urinal 1 is enlarged and thickened as at 14, and has an outlet or discharge opening 15 therein. A perforated screen or guard plate 16 is removably fitted in a countersink 17 in said opening. A drain or outlet passage 18 is provided in the portion 14 and is of less diameter than the opening 15, so as to provide for the formation of siphon elements below but in registration with said opening 15. A drain pipe 19 is connected in the usual manner with the urinal and registers with the passage 18.

Siphon means is housed within the enlarged portion 14 of the urinal and comprises a rectangular chamber 20 having its upper end opened just below the plate 16. A passage 21 is provided between the upper end of the chamber and passage 18 to permit overflow from said chamber into said passage.

The siphon comprises a cover 22 corresponding to the one 5, altho the cover 22 rests on the bottom of the chamber 20 and is perforated near its lower end as at 23. The upper closed end of the cover is spaced

from the core portion 24 and from the guard plate 16.

A siphon conduit 25 is formed in the core portion 24 and extends thru the portion 14 to the lower side thereof, where it is connected as at 26 with the upper end of the pipe 11. A similar conduit 27 is formed in the portions 14 and 24 and leads into the lower end of the drain passage 18. The upper ends of these passages 25 and 27 are approximately in the same plane at the top of the core 24 which latter terminates below the cover. The passage 25 is virtually an extension of the pipe 11 and a part of the trap 13.

Operation.

After a flushing operation and the tank is empty, the water is left at the level of the pipe 9, in the trap 8, and the pipe 11 draws the water from the intake side of the trap whereby the water in both sides of the trap is brought to the same level, namely, the top of the pipe 11. The pipe 11 conducts the water to the trap 13, to the upper end of the passage 25 from which the water spouts or flows with sufficient force against the cover plate 16 to dislodge any foreign matter which may have been lodged in the chamber 20. This also prevents clogging of the passage 25 and other siphon elements in the urinal, as these parts are thoroughly flushed by the action above described, after the flushing of the urinal. After the trap 8 is drained to the level of the top of the pipe 11, the level of the water in the pipe 11 descends until it reaches the level at the top of the passage 25, or in other words, balances in the trap 13. The water in the chamber 20 both on the inside and outside of the cover will siphon out thru the pipe 27 and the level thereof will be brought below the upper ends of the conduits 25 and 27.

When the tank 3 begins to fill, air which has entered thru the pipe 6 into the cover 5 and pipes 7 and 11 will be compressed by the water and the water is forced out of the intake sides of the traps 8 and 13 into the outlet legs or sides of said traps. The force of the air upon the top of the column of water in the cover 5 causes the level of this column to be maintained below the upper end of the pipe 7 so as to prevent flow of water out thru said pipe. The action of the compressed air maintains the traps with the outlet sides filled and the intake sides practically free of water, the air sustaining the weight of the columns of water in the outlet sides of the pipe so that the level of the water is at the pipe 9 in one instance and at the top of the passage 25, in the other instance. When the flushing tank is filled the pressure of the air on the siphons and traps is balanced by action of the weight of the columns of water and head water in the tank

itself. Thus upon the slightest disturbance of this balance the flushing operation will take place. Therefore, upon use of the urinal, some of the liquid will run thru the perforated guard plate 16 into the chamber 20 whereupon the level of the water therein will be raised. If this level is raised to the point where the water begins to run out thru the passage 27 (and that is usually the case upon use of the urinal) a siphon action will be started whereupon the water will run out of the passage 25 of the trap 13 and drain out thru the passage 27. Immediately upon the draining or siphoning of the water out of the trap 13, the weight of this water is reduced and is not sufficient to overcome the air pressure in the pipe 11. The air then expands and drives the water out thru the trap 13. Simultaneously with the action in the trap 13 the trap 8 operates and the air pressure is likewise reduced in the cover 5 whereupon the water will rise in said cover until it flows into the pipe 7. The water of the tank is then free to flow into the urinal thru the pipes 7, 9 and 10, and the pipe 11 and passageway 25. The head of the water in the tank also acts to siphon the tank thru the air intake pipe 6 and the urinal will be thoroughly flushed and the tank drained.

After flushing of the bowl and while the tank 3 is refilling the chamber 20 will be siphoned several times. When the water is level in the trap 13, as is the case immediately after a flushing operation, the level of the water in the chamber 20 will have been lowered to the line of perforations at the bottom of the cover, due to siphoning of the water therein out thru the passage 27 during the overflow of the pipe 11 while the water in seeking its level in the trap 13. This level in the chamber 20 will be raised during the time required in filling the tank 3, by seepage or draining of the small quantity of water collected on the sides and bottom of the bowl and due to the water forced out of the passage 25 into said chamber while the air is compressed in the pipe 11 by the action of the water against the air in the cover 5. When the level of the water in the chamber 20 reaches the level of the top of the passage 27 the water in said chamber will siphon out thru the passage 27 and drain the chamber until when the tank 3 is filled and the air compression ceases to force the water out of the passage 25 whereupon the level of the water in the chamber is lowered to a point below the tops of the passages 25 and 27 and the apparatus is again ready for an automatic flushing operation.

The passages 18, 25 and 27 are straight, substantially upright and in line with the opening 15, when open the plate 16 may be lifted out and ready access to these passages and the chamber 20 may be had in

order to clean out these elements. Thus it will be seen that those elements requiring cleaning from time to time may be reached and cleaned without disassembling the apparatus and requiring the employment of a plumber or skilled laborer.

The housing of the siphon and trap elements in the lower part of the urinal provides for a compact fixture and the construction of the siphon and trap elements is very simple and compact whereby the entire device is made cheaper as to construction, reliable in operation and easy to install and clean.

15 While I have shown the invention as applied to urinals it is obvious it may be applied to toilet bowls or other similar fixtures without departing from the spirit and scope of this invention.

20 Referring to Figs. 5 and 6.

I have shown a modified form of the invention wherein the bowl 30 may be formed of metal or porcelain. This form will be the same as the preferred form in general arrangement and operation but of necessity different as to form because of its being made of metal, as to the siphon elements, etc.

In this form the bowl has a drain opening 31 therein, provided with a countersink 32 upon which rests the lateral flange 33 of a short metallic pipe 34, which pipe depends from the bowl. A nut 35 holds the pipe in place and a drain pipe 36 of usual form is connected to the lower end of the pipe 34.

35 A partition 37 integral with the pipe 34 on one side thereof and with a horizontal bottom member 38, forms with the wall of the pipe 34 and member 38, a chamber 39 within the pipe 34. The upper edge of this chamber at the partition side terminates short of the upper end of the pipe 34 and allows for overflow into the pipe 34. The upper end of the pipe 34 supports a perforated guard or screen plate 31 which is removably countersunk in said upper end. A pipe 41 leads from the upper trap, not shown, (which trap corresponds to the trap 8 and the pipe to the one 11 of the preferred form of the invention), thru openings 42

50 and 43 in the side of the pipe 34, up into the chamber 39. A pipe 44 extends from the chamber 39, thru the bottom 38 and discharges into the pipe 36. The pipes 41 and 44 are substantially upright in the chamber 39 and have their upper ends open in the same horizontal plane at a point near but slightly below the upper end of the chamber.

A cover member 45 closed at its upper end is mounted in the chamber so as to house the upper portions of the pipes 41 and 44, the upper ends of said pipes being spaced slightly below the closed end of the cover. The lower portion of the cover has a series of perforations therein communicating the interior of the cover with the chamber 39.

The cover is circumferentially spaced from the pipes 41 and 44 and side wall of chamber 39.

The cover, chamber and pipe 44 provide a siphon and as the operation of this form of the invention is the same as in the other form, further description is thought to be unnecessary. The same advantages as to access to the siphon elements, etc., for cleaning thereof, attains in this form as in the preferred form.

I claim:

1. The combination with a flushing tank, of an air container therein having its top closed and its bottom open and in communication with said tank, a discharge pipe having its intake end within and spaced upwardly from the open end of said container, a trap to which said pipe leads, a bowl, a flushing pipe leading from the trap to the bowl, said bowl having a discharge opening, a chamber the upper end of which is open and in registration with the opening, a drain passage in said bowl in communication with said opening, a cover mounted in said chamber and having its upper end closed and its lower end in communication with said chamber, a conduit leading from a point within the cover to said drain passage and a pipe in communication with said air container arranged to discharge into the cover above the lower end thereof and formed as a trap intermediate of its ends.

2. The combination with a flushing tank, of an air container therein having its top closed and its bottom open and in communication with said tank, a discharge pipe having its intake end within and spaced upwardly from the open end of said container, a trap to which said pipe leads, a bowl, a flushing pipe leading from the trap to the bowl, said bowl having a discharge opening, a chamber the upper end of which is open and in registration with the opening, a drain passage in said bowl in communication with said opening, a cover mounted in said chamber and having its upper end closed and its lower end in communication with said chamber, a conduit leading from a point within the cover to said drain passage, another conduit leading from a point within the cover to said trap and formed to provide a trap intermediate of its ends.

3. The combination with a flushing tank, of an air container therein having its top closed and its bottom open and in communication with said tank, a discharge pipe having its intake end within and spaced upwardly from the open end of said container, a trap to which said pipe leads, a bowl, a flushing pipe leading from the trap to the bowl, said bowl having a discharge opening, a chamber the upper end of which is open and in registration with the opening, a drain passage in said bowl in communica-

tion with said opening; a cover mounted in said chamber and having its upper end closed and its lower end in communication with said chamber, a conduit leading from 5 a point within the cover to said drain passage, another conduit leading from a point within the cover to said trap and formed to provide a trap intermediate of its ends, said conduits having the ends thereof with-
10 in the cover in substantially the same plane and above the lower end of said cover.

4. The combination with a flushing tank, of an air container therein having its top closed and its bottom open and in communication with said tank, a discharge pipe having its intake end within and spaced upwardly from the open end of said container, a trap to which said pipe leads, a bowl, a flushing pipe leading from the trap to the 20 bowl, said bowl having a discharge opening, a chamber the upper end of which is open and in registration with the opening, a drain passage in said bowl in communication with said opening, a cover mounted in 25 said chamber and having its upper end

closed and its lower end in communication with said chamber, a conduit leading from a point within the cover to said drain passage and a pipe in communication with said air container arranged to discharge into the 30 cover above the lower end thereof and formed as a trap intermediate of its ends, said chamber at one side of its upper end opening into said drain passage.

5. The combination with a flushing tank, 35 of an air container therein having a closed top and an open bottom communicating with the tank, a conduit leading from the air container, a trap to which said conduit leads, a bowl, a flushing pipe leading from 40 said flushing pipe to said bowl, a chamber, a siphon communicating with the chamber, and a pipe communicating between the trap and the siphon, said bowl having a discharge opening with which the chamber, the siphon and last named pipe register, the legs of said siphon and said pipe being upright with 45 relation to and accessible for cleaning thru said opening.

DUDLEY NEWTON.
